BLIND GUIDE

Otto E. Edstrom, San Francisco, Calif.

Application June 27, 1944, Serial No. 542,387

6 Claims. (Cl. 135—47)

My invention relates to improvements in a guide for a blind person wherein the usually forwardly inclined and exploring cane is provided with a freely swivelled caster on the lower end thereof which operates in conjunction with a horizontally disposed wheel rotatably mounted immediately above said caster, to facilitate exploration of a contemplated course and to harmlessly contact and locate objects thereon or adjacent thereto, or corners, curbs or other impedimenta with which a path of the sightless may be beset.

The primary object of the present invention is to provide a new and improved guide for the sightless, by means of which all impedimenta upon or adjacent a contemplated path may easily be located.

Another object is to provide a new and improved device of the character set forth, having improved means for relieving the hand of an operator of the strain incident to exploration with a forwardly projected exploring cane.

A further object is to provide a new and improved device of the type described which easily may be constructed and operated with a minimum effort and having a maximum efficiency.

A still further object is to provide a new and improved guide for the peripatetic blind which may harmlessly contact objects within a projected course.

A still further object is to provide a new and improved cane or guide for the sightless whose projected or exploring end may easily and silently roll along a vertical as well as a horizontal surface without damage to either surface.

I accomplish these and other objects by means of the improved device disclosed in the drawings forming a part of the present application, and in which—

Fig. 1 is a side elevation of my device as in use;
Fig. 2 is a plan view of the device;

Fig. 3 is an enlarged broken plan view of the lower or supported end of the guide; and

Fig. 4 is an enlarged broken side elevation, partly in vertical section, of the lower portion of the guide.

Referring to the drawings:

The numeral 1 is used in general to designate a substantially inclined and preferably tapered cane having a vertical lower end 2 and a flattened horizontally disposed upper end or portion 3 and vertical shoulders 4, the purpose of which will hereinafter be more fully set forth.

Upon the lower or vertical portion 2 of the cane 1 is mounted a freely swivelled caster 6,

preferably provided with a cushioned tire 7 of rubber or other suitable resilient material. The spindle or pivot 8 of the caster 6 is rotatably mounted within a bore 9 within the bottom end 5 of the vertical portion 2 of the cane 1 and is provided with an annular groove engaged by a cross pin 12, inserted transversely through the cane 1 to retain said spindle in assembled position. A horizontally disposed wheel 14, having 10 a cushion tire 16, is rotatably mounted immediately above the caster 6, and preferably upon the pivot or spindle 8 thereof.

In operation:

A blind person grasps the flattened horizontal portion 3 at the upper end of the cane 1, the flat sides and shoulders 4 readily indicating by touch to an operator that the device is in a vertical or operative position, as disclosed in Fig. 1 of the drawings. That is to say that the lower end 2 of the cane 1 is substantially vertical so that the forwardly projected or exploring end of the cane 1 easily may be pushed forwardly ahead of the operator, as indicated by the straight arrows in Figs. 1 and 4 of the drawings, or freely 20 swung laterally in both directions, as indicated by the curved double arrow in Fig. 2 of the drawings, in order more easily to explore a contemplated path and locate adjacent objects or obstructions which might impede progress along a contemplated course, such, for instance as a side wall indicated at 17, or a corner or other abutment 18, or any other projecting obstacle, while the caster 6 may locate steps, curbs, or a sill 19.

While the lower end 2 of the cane 1, supported 35 by the caster 6 is moving forwardly or laterally, the substantially overhanging or laterally projecting rim of the wheel 14 and its cushion tire 16 may harmlessly contact and noiselessly roll along an adjacent vertical surface or contact objects without injury thereto.

It should be particularly noted that the caster 6 also operates as a substantial supporting means for the forwardly projecting and exploring end 2 of the cane 1, thereby relieving the hand and wrist of an operator of the weight of said projected cane and any strain incident thereto.

It should also be noted that the caster 6, being freely swivelled, may be moved forwardly as well as laterally with a minimum effort so that 45 objects or obstructions directly within a contemplated path easily may be located.

Having described my invention, I claim:

1. A blind guide comprising a cane; a rolling support upon the lower end of said cane; and a horizontally disposed wheel mounted upon the 55

lower end of said cane and above said rolling support.

2. A blind guide comprising a cane; a rolling support freely swivelled upon the lower end of said cane; a horizontally disposed wheel rotatable upon said cane and positioned directly above said rolling support thereon, and cushioning means mounted upon said horizontally disposed wheel.

3. A blind guide comprising a cane; a cushioned tired caster swivelled upon the lower end of said cane; and a horizontal wheel rotatably mounted upon said lower end of said cane.

4. A blind guide comprising a cane; a cushioned tired caster freely swivelled upon the lower end of said cane; a horizontal wheel rotatably mounted on said cane above said caster; and a cushioned rim mounted upon said horizontal wheel.

5. A blind guide comprising a cane having a

vertical lower portion and a substantially horizontal upper portion; a caster freely swivelled upon the lower end of said cane; a horizontally disposed wheel rotatably mounted upon the swivel pivot of said caster; and means upon the upper end of said cane to indicate operative position thereof.

6. A blind guide comprising a substantially inclined cane having a vertical lower end and a substantially horizontal upper end; a cushion tired caster freely swivelled upon the lower end of said cane; a horizontally disposed wheel rotatably mounted upon the swivel pivot of said caster; cushioning means mounted upon the rim of said horizontal wheel; and shoulders upon the horizontal upper end of said cane to indicate operative position thereof.

OTTO E. EDSTROM.
